CROSS-WIND POSITION CONTROL

George A. Spencer, Akron, Ohio, assignor to The Firestone Tire & Rubber Company, Akron, Ohio, a corporation of Ohio

Application April 16, 1949, Serial No. 87,943

1 Claim. (Cl. 242—31)

1

This invention relates generally to machines for winding filamentary material onto spools and, in particular, relates to a device for maintaining the traverse guide spaced at all times from the spool during winding.

In conventional winding machines the traverse guide is mounted for swinging motion and is constantly in contact, by the action of weights or other equivalent means, with the outer layer of the material being wound. This results in chafing of the threads in more or less degree, being very pronounced in the case of monofilaments such as the modern plastic threads, one example being "Velon" a product of The Firestone Tire & Rubber Company. In fact, with monofilaments of 8 gauge mil or less, it is scarcely possible to complete the winding of a single spool without a complete severing of the thread occurring at some point of the winding. The situation is also somewhat aggravated when the tubes or spindles of the machine are out of line. Also, filaments are more susceptible to chafing when wound directly following the extruding process, as in such case the filament is in a soft condition.

It is to the relief of these conditions that the present invention is directed, one object of the invention being to avoid chafing of material during winding.

More particularly, it is an object of the invention to provide a winding mechanism wherein the winding guide is constantly spaced from the outer layer of wound material, during winding, a further object being to provide such a mechanism which is easy of attainment by simple addition of parts to existing machines.

These and other objects are attained by the invention described in the accompanying specification and illustrated in the drawings, in which:

Fig. 1 is a top plan, partly broken away of the external or spool-holding portion of a winding machine showing the cross-wind mechanism at the beginning of a winding operation.

Fig. 2 is a view similar to Fig. 1 showing the parts in the position they occupy at a later stage of winding.

Fig. 3 is a partial side elevation of Fig. 1.

Fig. 4 is a detail taken on the line 4—4 of Fig. 2.

Fig. 5 is a view taken on the line 5—5 of Fig. 4.

Referring to the drawings by characters of reference, there is shown in Figs. 1 to 3 a winding machine constructed along generally conventional lines and comprising a framework, indicated as a whole by the numeral 1, which contains (not shown) the driving mechanism and the cam means for reciprocation of the traverse guide, such mechanism being well known in the art.

2

A driven spindle 2 extends from the housing 1 and serves to hold the fibrous spool 3, on which the filament 4 is to be wound. The spindle is provided with a collar 5 to serve as a limit stop for the spool 3, and beyond the collar the leftward portion 6 of the spindle is polygonal in cross-section to effect rotation-imparting engagement with the spool 3. Obviously other means of locking the spool to the spindle may be employed. The thread 4 is led over an elongated roller 7, supported on a frame 8 in alignment with the axis of the spindle 2, and is led through an eyelet 9 carried by a traverse guide 10 reciprocable along frame 8 by a connection with a rod 11 leading to the cam means (not shown). The frame 8 is carried on an arm 12 which is pivoted at 13 to the housing 1, and the arm 12 has a lower extension 14 below the pivot 13 constituting a counterweight tending to hold arm 12 in a vertical position. In conventional machines this counterweight, or equivalent means such as a spring, holds the traverse guide 10 against the thread on the spool as the arm 12 swings out due to increasing diameter of the spool, with resultant chafing. An arm 15 pivoted at 16 on arm 12 has a foot 17 engaging in an arcuate channeled member 18. The foot, which is held in place by an arm 19 under action of a spring 20, acts as a stop to prevent arm 12 from swinging counter-clockwise until released by pressure applied on arm 19. An adjustable limit stop for the arm 12 is provided in the form of a rider 21 on the arcuate member 18.

The spool 3 has a flared, conical inner end 22 to accommodate a shift axially of the spool of each succeeding layer of wound thread to produce the pattern shown in Fig. 2. This is conveniently accomplished by moving the spindle and spool outwardly of the machine a small amount for each layer of thread wound. The mechanism for thus shifting the spindle is actuated by the increasing diameter of the spool and comprises a roller 23 adapted to contact the outer layer of material at all times during winding, and which in its progress away from the axis of the spindle operates a bell-crank lever, shown generally at 24, to move the spindle axially. The roller is supported in a frame 25 which in turn is carried by a vertical screw-pivot 26 on one end of an arm 27 of the bell-crank. The arm 27 is connected to the other arm 28 of the bell-crank by means of a horizontal screw-pivot 29 which enables raising the arm 27 to facilitate access to the spindle as when a spool is being mounted or removed. The bell-crank lever as a whole is mounted on a bracket 30 on the

machine by means of a vertical pivot 31 fixedly carried by a side extension 32 on the arm 28. Pivot 31 extends downwardly through the bracket 30 and is surrounded by a torsion spring 33 fixed to the bracket 30 at one end and at its other end to a washer 34 keyed to the pivot 31. The spring 33 thus urges the roller 23 constantly toward the axis of spindle 2. A stop 35 abuts against the extension 32 to define the lower or working position of the roller 23, and a stop 36 depending from the inner end of arm 27 limits the extent of outward movement of the roller 23.

The outer end of arm 28 carries a lug 37 (Figs. 3, 4, and 5) pivoted at 38, which engages between 15 a pair of collars 39 on the spindle 2 to transmit motion of the bell-crank thereto.

With the construction thus far described, all of which is conventional, as the diameter of the spool of thread increases, the roller 23 will move 20 away from the axis of spindle 2 and lug 37 will move spindle 2 outwardly of the machine by a corresponding amount.

According to the invention, means are provided to utilize motion of arm 28 of the bell-crank lever to maintain traverse guide 10 a fixed distance from the wound thread at all times during winding. Referring to Figs. 4 and 5, an angular extension 40 is provided on arm 28 and into a bore therein is fixed a reduced extension 41 of a rod 42 with a roller sleeve 43 screw fastened to a lower reduced portion thereof. The roller 43 contacts a cam 44 fixed to the traverse-guide-holding frame 8. The edge 45 of the cam is angularly directed with respect to the axis of spindle 2 (Fig. 2) and is concentric with pivot 13 (Fig. 3). The edge 45 is so designed that as the lug 37 moves leftward in response to outward progress of roller 23 the cam contacting roller 43 moves the cam so as to rock frame 40 about pivot 13 and keep the traverse guide 10 at a small distance from the outer thread layer. Preferably this distance will be of the order of one-sixty-fourth inch ($\frac{1}{64}$ ") to one-sixteenth inch ($\frac{1}{16}$ "), although shown exaggerated in Fig. 3. 45

It will be noted that in the action just described the contact roller 23 and its associated mechanism serve the double purpose of causing

axial movement of the spindle and of maintaining clearance at the traverse guide.

It will be seen that provision has been made for axial motion of the spool and continued clearance of the spool from the traverse guide through the medium of a contact roller and the assistance of cam action, the contact roller and traverse guide move away from the spool.

While a certain embodiment has been shown, obviously changes in the precise shape, character and arrangement of the various parts may be made without departing from the scope of the invention.

What is claimed is:

In a winding machine, a spindle arranged for axial motion and held against motion transverse to its axis, a roller adapted to continuously contact material being wound on a spool carried by said spindle and to recede from the axis of the spindle as the diameter of said spool of material increases, a traverse guide on an arm mounted on a pivot for recession from the spindle as the wound spool increases in diameter, a bell-crank lever connected to the contact roller and arranged to move the spindle axially as the contact roller recedes from the spindle, cam means on the traverse guide having a cam edge concentric with the said pivot and angular to the spindle axis, and follower means on said lever adapted to contact said cam edge to move the traverse guide away from the spindle as the latter is moved axially.
